Garrett Smith, of Philadelphia, Pa. and
Henry Brown, "

Assignors to

Marshbank and McConkey, of Lancaster, Pa.

Letters Patent No. 2153. Dated Aug. 1, 1865.

Ante-dated July 4, 1865.

Design for the Plates of a Cook's Stove.

The schedule referred to in these Letters Patent and making part of the same.

To all whom it may concern:

Be it known that we, G. Smith and H. Brown (a/cres
to Marshbank and McConkey) of Philadelphia, County of Philadelphia
and State of Pennsylvania, have invented or produced a new and or-
iginal design for the plates of a cook stove, termed the "Loyal States," and
we do hereby declare the accompanying Drawing with the following
explanation of the same, to form a full, clear and exact description
of the said Design.

In the drawing

Fig. 1, is a perspective view of the "Loyal States" cook-stove,

Fig. 2, represents one of the side plates,

Fig. 3, the back plate, and

Figs. 4 and 5, two of the feet.

A is the upper top-plate, B the lower top-plate and C the base
plate of the stove; and round the edges of the plate B, and at the side edges
of the plate A is the plain beading a. At the front edge of the plate A is
an ornamental beading c, and round the edges of the plate C is an
ornamental beading e. Near the edges of the side-plate D is a plain bead-
ing, a similar beading enclosing a panel on the upper front-plate C,
at each side of which are the ornamental figures shown in Fig. 1, and

at the edges of the lower front-plate H is an ornamental beading b.

To the plate H are hung two doors II, and to the plate D is hung a door I, and round all the doors and round a panel K on the plate D is a plain beading d.

In the centre of each of the doors II, and also in the centre of the door I, the panel K and plate C is a boss which is surrounded by a number of smaller bosses, and round the central ornament in the door I, panel K and plate C are the ornamental figures and forms shown in the drawing.

On the back-plate I are three oblong panels, each edged by a plain beading and having in the centre an ornamental figure of the character shown in Fig. 3.

At the upper part of each leg is a boss, surrounded by a number of smaller bosses, this ornament being inclosed by the foliated figures shown in Figs 5 and 6.

We claim—

The ornamental figures and forms, substantial by as illustrated, in and by the accompanying drawing, the whole forming an ornamental design for the plates of the "Loyal States" Book Stove.

In testimony whereof we have signed our names to this specification in the presence of two subscribing witnesses.

Witnesses.
